SKIERS' TOW SEAT

Ivor J. Alsop, Box 23, Bellingham, Wash.
Filed July 9, 1962, Ser. No. 208,324
3 Claims. (Cl. 104—173)

This invention relates to a tow seat, and more particularly to a tow seat for use in pulling skiers easily and safely and conveniently up a hill using an ordinary rope tow.

The primary object of this invention is to provide a tow seat which is constructed so that it will free itself from the rope as soon as pressure is released from the seat end, the tow seat of the present invention including a cable which has a kink therein which provides a spring-like action to kick the grip off the rope when backward pressure on the tow seat is released.

A further object is to provide a tow seat of the type stated which will permit a ski tow to be used with increased safety, and wherein one form of the tow seat is adapted to include a rigid shaft while a different form has a flexible shaft instead of the rigid shaft.

Still another object is to provide such a tow seat that is economical to manufacture and efficient in operation and which is rugged in structure and foolproof in use.

These and other objects of the invention will become apparent from a reading of the following specification and claims, together with the accompanying drawings, wherein like parts are referred to and indicated by like reference characters and wherein:

FIG. 1 is an elevational view illustrating the tow seat of the present invention.

FIG. 2 is a view illustrating the hook member or grip per se.

FIG. 3 is a view looking at the opposite side of the hook member from that shown in FIG. 2.

FIG. 4 is a fragmentary elevational view showing the gripping of the tow rope by the hook member.

FIG. 5 is a sectional view taken on the line 5—5 of FIG. 3.

FIG. 6 is a fragmentary sectional view illustrating certain constructional details of the present invention.

FIG. 7 is a view illustrating a modified tow seat.

Referring in detail to the drawings, and more particularly to FIGS. 1 through 6 of the drawings, the numeral 10 indicates the tow seat of the present invention which is shown to comprise a seat member that is indicated generally by the numeral 11, and the seat member 11 includes coplanar end portions 12 as well as an intermediate offset portion 13. The numeral 14 indicates a tubular rigid shaft which is connected to the intermediate portion 13 of the seat member 11, and caps 15 and 16 are suitably connected to the end portions of the shaft 14. The numeral 17 indicates a securing element which is arranged as shown in FIG. 1.

As shown in the drawings, a cable 18 extends from the shaft 14, and a portion of the cable 18 may extend through a suitable small opening or aperture 19 in the cap 16, as shown in FIG. 6, and a clip 20 may be provided for maintaining or retaining the cable 18 in its proper connected position relative to the shaft 14.

The cable 18 has a kink 21 therein for a purpose to be later described. As shown in the drawings, a hook member 22 is suitably affixed to an end of the cable 18, and the hook member 22 is shaped to include a main body portion 23 which has a generally rounded surface, and the main body portion 23 also has an elongated recessed area 24 which helps reduce the weight of the hook member, FIG. 3. An end of the portion 23 is slightly enlarged as at 25, and the enlargement 25 terminates in a curved lug portion or finger portion 26, and as shown in the drawings the lug portion 26 is slightly offset from the

2

main body portion 23 whereby the lug portion 26 is arranged angularly with respect to the main body portion. As shown in FIG. 4, when the device is being used, the tow rope 28 is adapted to be engaged or gripped between the lug portion 26 and a shoulder 27 on the hook member 22.

Attention is now directed to FIG. 7 of the drawings wherein there is illustrated a modified tow seat which is indicated generally by the numeral 10', and the tow seat 10' has a construction which is somewhat similar to the previously described tow seat 10. However the tow seat 10' includes a shaft 14' which is of flexible or yieldable material instead of the rigid shaft 14 shown in FIG. 1. Also in FIG. 7 the numeral 29 indicates the connection between the seat member 11 and the shaft 14'.

As shown in FIG. 7 a suitable retainer 30 is adapted to be affixed to an end of the seat member 11 as at 31, and the retainer 30 includes a loop portion 32 which is adapted to selectively receive or be engaged by the lug portion 26 of the hook member 22 for a purpose to be later described.

In FIGS. 3 and 5 the numeral 33 indicates a clip or fastener which is suitably affixed within the recessed portion 24, and the clip 33 provides a means for affixing or connecting the hook member 22 to the cable 18.

From the foregoing, it will be seen that there has been provided a tow seat for use by skiers, and in use with the parts arranged as shown in the drawings, when the tow seat of the present invention is being used, the shaft 14 is adapted to be arranged between the legs of the skier, and the member 11 is adapted to be positioned rearwardly of the buttocks, so that with the rope 28 actuated in the usual manner, and with the hook member 22 engaging the rope 28 as shown in FIG. 4, the skier can be conveniently and safely pulled up a hill by means of the ordinary rope tow 28.

The parts can be made of any suitable material and in different shapes or sizes.

The present invention is adapted to be used for pulling skiers up a hill by means of an ordinary rope tow with very little effort and with a higher degree of safety than is possible with other methods or means. The present invention includes the clamp or hook member 22 which binds on the rope 28 when backward pressure is applied to the extended handle. The flexible line or rope or cable 18 is attached to the end of the shaft or handle 14 or 14', and the cable 18 is connected to the handle portion 23 of the clamp 22 as at 33. The seat member 11 is arranged and attached so that the shaft 14 or 14' can be conveniently placed between the skier's legs whereby the skier can sit on the seat member and ride effortlessly to the top of the tow. The clamp or member 22 is constructed so that when backward pressure on the handle portion 23 is released, the clamp 22 falls off the tow rope 28 due to the provision of the kink 21 in the cable 18.

With further reference to the form of the invention shown in FIGS. 1 through 6, the shaft 14 is adapted to be made of a suitable material such as aluminum, and the device of FIGS. 1 through 6 is of a type that is adapted to be sold to area operators and it is intended that it will be the responsibility of the tow operator to get the tow seat back to the bottom of the hill. With reference to the device 10' shown in FIG. 7, there is provided the flexible hose or shaft 14' which may be made of a suitable material such as rubber or plastic and the form of the invention shown in FIG. 7 is of the type that is adapted to be used and sold to the individual skier, and the flexible shaft 14' is provided so that the device can be wrapped around the waist like a belt while not in use, and, for example, the loop portion 32 is adapted to receive an end of the member 22 so as to permit convenient wrap-

ping of the device around the waist when the device is not being used and this is illustrated in FIG. 7.

It is to be noted that in both forms of the invention, a kink 21 is arranged in the cable 18 so that it acts like a spring and kicks the grip off the rope when backward pressure is released, and wherein the hook member will move from a position substantially parallel to the tow rope 28, to a position substantially at right angles to the tow rope 28, when the hook member comes off of the tow rope at the top of a hill.

As shown in FIG. 4, the hook member 22 is adapted to firmly grip or engage the rope 28 in order to prevent slippage on the rope.

The element 17 shown in FIG. 1 can be used for suspending the device 10 from a suitable structure or support member as, for example, when the device 10 is not being used.

It will be seen that according to the present invention there has been provided a tow seat which includes the tow grip attached to a seat for pulling skiers effortlessly and safely up a hill on an ordinary rope tow such as the rope tow 28, and the present invention is constructed so that it will free itself from the rope as soon as pressure is released from the seat end.

In use, the skier will take a tow seat from a rack at the bottom of the hill and deposit it at the top of the hill on specially designed racks which can be skied down to the bottom with approximately 100 tow seats at a time, and in some instances it may be desirable to send them down by means of a tight line. The reason for this method of distribution is that if all skiers have them available, it will not be necessary to operate a tow at high speed since the same productivity can be gained from the tow by gearing it down and putting the skiers on closer together as desired or required.

The tow seat of the present invention will make a ski tow safer for a number of reasons such as the following. The skier will be traveling at a lower than usual speed, the skier will not be directly attached to the rope and will be less likely to get clothing and the like entangled in the rope, and the skier is not attached to the rope as he or she would normally be with a conventional tow grip and in case of an accident such as a fall, the seat merely slips from between the skier's legs and the hook drops off the rope. Also, all ordinary safety measures such as a safety gate will have a better chance to operate because the rope will not travel as far due to the reduced momentum. Also, the upruns can be maintained better due to the reduced speed of the skier, and there will be less chance for burns due to the reduced speed and because a smooth slick rope such as a multi-filament rope will be ideal whereas with ordinary tow systems a coarse rope with good adhesion is essential.

In addition, the present invention has certain other important advantages or features to the operator using the tow seat such as the following. There will be a saving on rope because it cuts out the excessive abrasion

that goes with high speed, and there will be a saving on wheel bearings, pulleys and maintenance due to the reduced speed. Also skiing will be made more enjoyable, that is skiing by rope will be made more convenient and pleasant, and there will be an increase in the number of rope tow users due to the increased safety and convenience. An important feature is the economy which will result from the use thereof. Also the tow seat of the present invention will save wear and tear on gloves, trousers, parkas, sweaters and the like and will thereby permit the operator to derive increased benefits such as financial savings, and such financial savings will be beneficial to the skiers as well as the operators.

Minor changes in shape, size and rearrangement of details coming within the field of invention claimed may be resorted to in actual practice, if desired.

What is claimed is:

1. A skier's tow seat for use with an overhead tow rope, said tow seat consisting solely of a seat member, 20 a shaft connected to the intermediate portion of said seat member, and said shaft adapted to be extended between the legs of the user, a cable extending from said shaft and connected thereto, said cable having a permanent kink therein, a hook member connected to said cable for selectively engaging the tow rope, and wherein the hook member is not permanently attached to the tow rope, the kink in the cable causing the hook member to rotate and move from a position substantially parallel to the tow rope, to a position substantially at 25 right angles to the tow rope so that the hook member will come off of the tow rope the instant that backward pressure is released from the seat member or cable, said hook member including a main body portion that has a generally rounded surface, an end of said main body portion being enlarged and terminating in a curved lug portion, said lug portion being slightly offset from the main body portion so that the lug portion is arranged angularly with respect to said main body portion, there being a shoulder on said hook member, and the tow 30 rope adapted to be engaged and gripped between the lug portion and shoulder on the hook member when the tow seat is being used.

2. The structure as defined in claim 1 wherein said shaft is rigid.

3. The structure as defined in claim 1 wherein said shaft is flexible.
